UNITED STATES PATENT OFFICE

162,053

FILM VIEWER

Leslie Mann, San Gabriel, Calif.

Application October 11, 1950, Serial No. 12,525

Term of patent 14 years

(Cl. D61—1)

To all whom it may concern:

Be it known that I, Leslie Mann, a citizen of the United States and a resident of San Gabriel, in the county of Los Angeles and State of California, have invented a new, original, and ornamental Design for a Film Viewer, of which the following is a specification, reference being had to the accompanying drawing, forming a part thereof:

I claim:

The ornamental design for a film viewer, substantially as shown and described.

LESLIE MANN.
